UNITED STATES PATENT OFFICE.

HARRISON H. EATON, OF BEVERLY, MASSACHUSETTS, ASSIGNOR TO UNITED SHOE MACHINERY COMPANY, OF PATERSON, NEW JERSEY, A CORPORATION OF NEW JERSEY.

STRIPPING-MACHINE.

1,161,038.

Specification of Letters Patent. Patented Nov. 23, 1915.

Application filed January 9, 1913. Serial No. 741,020.

To all whom it may concern:

Be it known that I, HARRISON H. EATON, a citizen of the United States, residing at Beverly, in the county of Essex and State 5 of Massachusetts, have invented certain Improvements in Stripping-Machines, of which the following description, in connection with the accompanying drawings, is a specification, like reference characters on the drawings indicating like parts in the several figures.

This invention relates to cutting machines and is herein illustrated in connection with a machine for cutting a hide into strips.

15 In machines of this class considerable difficulty has been experienced in feeding the hide properly into position beneath the knife. Hitherto this feeding has been accomplished manually and has been attended with considerable danger; and the general object of the 20 present invention is to provide a suitable feed mechanism which is much more effective and safe than the old hand method.

One feature of the present invention comprises in a machine of the class described a cutting block, a stripping knife, means for reciprocating said knife, a support for a piece of stock, and means independent of the stripping knife and under control of the operator for drawing said piece along said support and stopping it in position to be severed by said knife. This and other features of the invention including certain details of construction and combinations of 35 parts will be described in connection with an illustrative machine and pointed out in the appended claims.

Referring now to the accompanying drawing, the figure shows in perspective a portion 40 of a machine in which the present invention is embodied.

The frame 1 of the machine supports a cutting block 3 with which a stripping knife 5 co-operates, said knife being carried by a cross-head 7 supported by rods 9 which are vertically slidable in suitable bearings in the frame. The reciprocation of these rods from the counter shaft 11 is accomplished through two similar sets of connecting members, and 45 hence only one set will be described. Each rod is fast at its lower end to a block 15 having a groove which embraces a suitable

guide 17 formed on the frame of the machine whereby said block may slide vertically. And embracing this sliding block and 50 pivoted to it at 19 is a lever 21 which forms part of a toggle, the other lever of the toggle being shown at 23. To the knuckle 25 of the toggle is pivoted an operating link 27, said link at its opposite end having an eye 60 which embraces a crank pin on the counter shaft 11. The counter shaft is driven from a continuously rotating driving shaft 29 by means of a pinion 31 fast to said shaft and a gear 33 which may be connected by a Horton clutch with the counter shaft so as to cause said counter shaft to make one revolution and come to rest. The details of this clutch and of the brake 35 which prevents overrunning of the counter shaft will not be 65 described in detail since the particular one-revolution clutch made use of is immaterial so far as the present invention is concerned. It should be understood, however, that when the hand lever 37 is depressed the knife 5 70 will be caused first to descend upon the cutting block 3 to cut off a strip of stock and then to rise and come to rest in the position shown. A long wide stock table, a portion 75 of which is shown at 36, extending rearwardly from the cutting block and having its upper surface in the same plane as the upper surface of said block, supports the hide or other piece of stock which is to be cut, the forward end of said hide being 80 drawn through beneath the knife and upon the table 39 after each operation preparatory to the next one.

The machine as thus far described is old and well known, and no further detailed description will be given.

In manipulating the machine it has been customary for the operator to stand in front of the table and to reach under the knife or through the openings in the cross-head 95 between the operations in order to get hold of the forward portion of the hide. Such reaching, besides being a slow procedure is dangerous since a premature throwing in of the clutch may easily cause serious injury to the operator. The object of the present invention, as has been stated, is to do away with this manual feeding of the hide and thereby to increase the capacity 100

of the machine as well as to remove all liability of injury to the operator.

From a pulley 41 on the driving shaft a belt 43 leads over a pulley 45 on a stud shaft to which is fast a gear 47. This gear meshes with the larger gear 49 on a shaft 51 to which is fast a feed roll 53, the upper portion of said feed roll protruding through the surface of the casting in which the shaft 10 51 is mounted, the upper surface of said casting being an extension of and forming a substantial portion of the surface of the stock supporting table. This roll is thus rotated continuously but will not act to feed 15 the hide forwardly to the knife until said hide is pressed down upon said roll. In order so to press the hide when desired a normally idle feed roll 55 is rotatable on a spindle which is held by crank arms 57, 20 said arms being fast at their forward ends to a rock-shaft 59 which may be rocked through arms, one of which is shown at 61, connecting rods, one of which is shown at 63, and a treadle 65, a spring 66 serving 25 normally to hold said treadle in raised position.

Hides, which are the material usually operated upon by this machine, almost never lie flat upon the table but are more or less 30 warped or twisted so that their forward edges will not pass readily between the feed rolls. In order, therefore, to guide properly a misshapen hide a flaring guide 67 is located at the rear of the rolls 53, 55, said 35 guide serving to crowd the hide or other stock down upon the stock table.

In order to limit the forward movement of the hide and thus predetermine the width of the strip which is to be cut off, the table 40 39 is provided near each end with sockets 69 to receive stop pins 71.

The operation of the machine is as follows:—The stop pins 71 are set at the desired distance from the plane of the knife 45 5, and a hide is laid upon the table 36 with its forward edge overlying the continuously rotating roll 53. The treadle 65 is depressed thereby rocking the upper roll 55 downwardly so as to press the hide against the 50 roll 53 whereupon the hide is fed forward until its forward edge contacts with the stop 71. The treadle 65 is then released and the lever 37 depressed to throw in the clutch and cause the knife to make a reciprocation. The strip of stock which has been 55 cut off is removed and the operation of the machine is repeated. In this way, a hide or other piece of stock may be rapidly cut into strips of a desired width without exposing the operator to any possibility of injury.

Although the invention has been set forth in connection with a particular machine it should be understood that the invention is 60 not limited in the scope of its application

to the particular machine shown and described.

Having thus described my invention, what I claim and desire to secure by Letters Patent of the United States is:—

1. A machine of the class described having, in combination, a cutting block, a stripping knife, means for reciprocating said knife, a support for a piece of stock, and means independent of the stripping knife and under control of the operator for drawing said piece along said support and stopping it in position to be severed by said knife. 75

2. A machine of the class described having, in combination, a cutting block, a stripping knife, means for reciprocating said knife, a support for a piece of stock, means independent of the stripping knife and under control of the operator for drawing said piece along said support and stopping it in position to be severed by said knife, and a stop for limiting the movement of said piece and thereby determining the width of the strip which is to be cut off. 90

3. A machine of the class described having, in combination, a cutting block, a stripping knife, means for reciprocating said knife, a support for a piece of stock, a continuously rotating feed roll extending through said support into position to engage the underside of said stock, and means independent of the stripping knife and under control of the operator for pressing said piece down upon said roll and for raising 100 the pressing means. 95

4. A machine of the class described having, in combination, a cutting block, a stripping knife, means for reciprocating said knife once and bringing it to rest, a support for a piece of stock, a continuously rotating feed roll extending through said support into position to engage the under side of the stock, an idle feed roll normally held above the stock opposite the first-named roll, 105 and means for lowering said idle roll into contact with the stock to press said stock against said continuously rotating roll. 110

5. A machine of the class described having, in combination, a cutting block, a stripping knife, means for reciprocating said knife once and bringing it to rest, a support for a piece of stock, a continuously rotating feed roll extending through said support into position to engage the under side 120 of the stock at a point in the rear of the knife, an idle feed roll normally held above the stock opposite the first-named roll, a flaring guide extending upwardly and to the rear of the said idle roll, and means for lowering said idle roll into contact with the stock to press said stock against said continuously rotating roll. 125

6. A machine for cutting a piece of leather into strips having, in combination, a cutting 130

block in front of which the operator stands, a stripping knife normally held at rest above said block, means for causing said knife to make one reciprocation and then come to rest, a support for a piece of leather extending from the rear of the machine and located on that side of the knife opposite to the operator, and means under control of the operator and independent of the knife for draw-

ing the piece of leather toward said operator.

In testimony whereof I have signed my name to this specification in the presence of two subscribing witnesses.
